UNITED STATES PATENT OFFICE.

HENRY K. SANDELL, OF CHICAGO, ILLINOIS, ASSIGNOR TO MILLS NOVELTY COMPANY, OF CHICAGO, ILLINOIS, A CORPORATION OF ILLINOIS.

ELECTROMAGNETIC DEVICE.

Original application filed June 14, 1922, Serial No. 568,226. Divided and this application filed October 13, 1924. Serial No. 743,282.

The present invention relates to an electromagnet device, which is particularly adapted for use in connection with piano playing devices, but which may be used in other situations. In a piano playing device, the improved electromagnet device may be usefully employed for various purposes. For example, it may be employed for the purpose of controlling the position of a hammer-rail, or it may be employed for controlling the position of a damper.

In means of the character referred to, the improved device can be most advantageously used in an embodiment in which the armature of one electromagnet serves to actuate and releasably hold an actuating member employed in connection with the piano action, and the armature of another electromagnet serves to interlockingly engage the first-mentioned armature and prevent its return to its initial position until the armature of the second-mentioned magnet is withdrawn by energizing its coil.

The present application constitutes a division of Sandell application No. 568,226, filed June 14, 1922. The invention is illustrated in one preferred embodiment in the accompanying drawings, in which—

Fig. 1 is a broken vertical sectional view of a piano playing device, showing also the improved electromagnet device used in conjunction therewith; Fig. 2, a broken front elevational view of the mechanism shown in Fig. 1; Fig. 3, a broken sectional view showing the construction of the electromagnet device; Fig. 4, a broken plan view of the device shown in Fig. 3; and Fig. 5, a diagrammatic view illustrating the manner in which the hammer-rail of the piano action is controlled by the improved electromagnet device.

It may be stated that in a piano action, one method of controlling expression is by limiting the range of movement of the hammer. This may be accomplished by controlling the position of the hammer-rail which limits the swing of the hammer away from the string, thus regulating the stroke of the hammer.

One useful application of the improved electromagnet device is illustrated in the drawings in which the electromagnet device is employed to control the position of the hammer-rail.

In the construction illustrated, A represents the frame upon which are supported the strings A' of the piano; B, a bracket carried by said frame, and upon which is mounted the piano action B', which is equipped with a hammer B² and a hammer-rail B³; C, a jack-butt of the piano action; D an electromagnet for actuating the jack-butt; E, an actuating lever adapted to retract the hammer-rail to the position shown in Fig. 1; and F, an electromagnet device comprising a pair of electromagnets having interlocking armatures, one of which is adapted to actuate the lever E.

The piano action illustrated is, in its general construction, well known, and need not be described in detail.

The hammer B² is actuated through the medium of the usual mechanism by means of the jack-butt C. The jack-butt C is actuated by a riser 1 which is carried by the movable core 2 of the electromagnet D. The magnet D may have its coil energized by an alternating current, and when energized will lift the core 2 and actuate the jack-butt C through the medium of the riser 1, thus causing the hammer to strike the string.

The hammer-rail B³ is equipped with arms 3 (one shown) which are mounted on pivots 3^a carried by the bracket B.

The lever E has its central portion mounted on a pivot 4 carried by a member of the bracket. A spring 5 tends to draw the hammer-rail towards the strings. The upper end of the lever E is disposed back of and engages a felt covered stud 6 which projects from the end of the hammer-rail. The lower end of the lever E bears against the end of the armature, or core, of the actuating electromagnet of the device F.

The device F comprises an actuating magnet F', and a locking or latching magnet F². Magnets F' and F² are controlled by electric circuits, preferably carrying alternating current, as will be presently described. The magnet F' comprises a coil 7 encircling a tube of non-magnetic material 8; a laminated iron frame 9 forming a magnetic circuit about the coil, one side of the frame comprising, however, a plate 9^a carried by an angle 10; and a laminated core 11 which normally occupies a retracted position, but which is adapted to be drawn into the coil 7 when the latter is energized. The core 11

is equipped with a stem 12 which works through a felt bushing 13 which extends through the end of the frame 9. The member 13 extends inside of the frame and is member 5 circled by a bearing 14 having a conical seat conforming to the conical end 11^a of the core. The stem 12 is equipped at its outer end with a head 12^a which is provided with a recess in which is seated a felt disk 15 which engages the lower end of the lever E. Interposed between the head 12^a and the end of the frame 9 is a felt washer 16. When the magnet F' is energized, the core 11 is drawn into the coil 7, thus moving the lever E to the position shown in Fig. 1 and thereby retracting the hammer-rail B².

The magnet F² is disposed at right angles to the magnet F', and its armature is adapted to be projected by means of a spring and caused to interlock with the armature of the magnet F'. In this manner, the armature of the magnet F' may be held in the projected position shown in Fig. 1 until the magnet F² is energized.

The magnet F² comprises a coil 17 through which extends a tube of non-magnetic material 18; an iron frame 19 which extends about the coil in a longitudinal direction; a core 20 movable in the tube 18, and a spring 21 adapted to project the core to a position shown in Figs. 1 and 3. The core 20 is equipped, at its ends, with projecting stems 20^a and 20^b which work through bearings 22 and 23 with which the ends of the tube 18 are fitted. The lower end of the spring 21 bears against the inner end of the bearing 23. The stem 20^a is equipped with a head, or pad 24 which is adapted to interlock with the head with which the armature of the magnet F' is provided, as shown in Fig. 1.

Fig. 5 illustrates the manner in which the hammer-rail B² may be controlled by the magnet device F. In this figure, 25 represents a metallic track-bar, or roll, of a self-playing piano. One main 26 of an electric circuit is connected with the member 25. The other main 27 has a branch 27^a leading to one end of the magnet F² and a branch 27^b leading to one end of the magnet F'. From the other end of the magnet F², a conductor 28 leads to a contact 29 which is adapted to co-act with the tracker-bar 25. From the other end of the magnet F' the conductor 30 leads to a contact 31 which is adapted to co-act with the tracker-bar 25. Additional contacts 32 are shown, which co-act with the bar 25. These contacts have conductors 32^a which lead to the electromagnets D which serve to actuate the piano actions in a well known manner. A note sheet, or music roll, 33 is interposed between the contacts mentioned and the tracker-bar 25, it being understood that any one of these contacts may 60 come into contact with the bar 25 when a

suitable slot in the note sheet permits such action.

It will be seen that the contact 31 controls the action of the magnet F'. The note sheet may be provided with a series of expression-controlling slots co-acting with the contact 31. When the contact 31 engages one of these slots, it closes the circuit of the magnet F', thereby causing the core 11 to be drawn into the magnet, and thus actuating the lever E and causing it to retract the hammer-rail B² so that the hammer will be permitted a greater amplitude of movement. When the armature 11 is actuated, the armature 20 is projected by the spring 21, thus causing the armature 11 to be locked, or latched, in the projected position. Thus, the hammer-rail will remain in retracted position until the contact 29 engages one of a series of slots which control the action of the magnet F². In the mean time, the circuit through conductor 30 may be broken. When the circuit is closed through the conductor 28, the magnet F² is energized, and thus the armature 20 is withdrawn or retracted. This permits the lever E to be returned to its normal position by the spring 5, the lever E, in turn, forcing the magnet 11 to the partially ejected position which it normally occupies, as shown in Fig. 3.

While the magnet device has been illustrated for use in controlling expression by controlling the position of the hammer-rail, the magnet device may be employed for any similar purpose, as for example, to control the position of the damper 34 shown in Fig. 1. The damper is connected with actuating mechanism 34^a of well known construction, and a spring 35 tends to throw the damper against the strings. The damper may be retracted through the medium of a suitable member 36. This member 36 may constitute a portion of an actuating member which is adapted to be controlled by a magnet device F of the same construction and operating in the same manner as has been illustrated with reference to the control of the hammer-rail. It is unnecessary to illustrate and describe a duplicate of the magnet device F for use in controlling the action of the damper, as this will be readily understood by those skilled in the art in view of the explanation of the improved device shown in connection with the hammer-rail.

It is preferred to employ an alternating current for operating the electromagnet device F, and the letters A. C. are employed in Fig. 5 to indicate the use of an alternating current.

It will be understood by those skilled in the art that it is possible to readily control the position of the hammer-rail, or other expression device, by means of the improved magnet device; that the hammer-rail may be retracted at the instant desired by means of

the magnet F', whose circuit is closed only for a very brief period; and that the release of the hammer-rail may be effected by means of the magnet F² at any desired instant by 5 energizing the magnet F².

The foregoing detailed description has been given for clearness of understanding only, and no unnecessary limitations should be understood therefrom, but the appended 10 claims should be construed as broadly as permissible, in view of the prior art.

What I regard as new, and desire to secure by Letters Patent, is:

1. An electromagnet device comprising a 15 solenoid equipped at one end with a tubular guide, a non-magnetic tube within said solenoid, a magnetic core movable in said tube and equipped with a stem projecting through said guide, a head mounted on the projecting end of said stem, a second solenoid having an axis so disposed as to intercept said head when said core is in inoperative position, a non-magnetic tube extending through said second-mentioned solenoid and equipped 20 with end caps having perforations therethrough, a magnetic core in said last-mentioned tube having rod-like extensions extending through said perforations, a head secured to one of said extensions adapted to 25 interlockingly engage said first-mentioned head, and a spring interposed between said second-mentioned core and the opposing cap.

2. An electromagnet device comprising a 30 rectangular magnetic frame having a tubular guide extending through one end thereof, a non-magnetic tube mounted in said frame and extending through the other end thereof, a solenoid upon said non-magnetic tube, a 35 magnetic core movable in said non-magnetic

tube and equipped with a stem projecting 40 through said guide, a head mounted on the projecting end of said stem, a cushioning pad interposed between said head and said frame; and a second electromagnet device 45 comprising a rectangular magnetic frame having a non-magnetic tube extending through both ends of said frame and disposed at right angles to the first-mentioned non-magnetic tube, said second-mentioned non-magnetic tube being equipped with end 50 caps provided with perforations serving as guides, a magnetic core in said second-mentioned non-magnetic tube equipped at its ends with stems working through said guides, one of said stems being equipped 55 with a head adapted to interlock with said first-mentioned head, a spring confined between the core and the end cap at the opposite end of the core, and a solenoid within said second-mentioned frame encircling said 60 second-mentioned non-magnetic tube.

3. In means of the character set forth, a 65 rectangular frame of magnetic material having perforations through its end portions, a solenoid within said frame, a magnetic tube within said solenoid having its end portions projecting through said perforations and equipped with plugs provided with axial perforations, a magnetic core within said tube equipped with stems working through 70 said last-named perforations, a coil-spring interposed between said core and one of said plugs, a head carried by the projecting end of the stem at the other end of the device, and a cushioning member interposed between 75 said head and the adjacent plug.

HENRY K. SANDELL.
